UNITED STATES PATENT OFFICE.

GEORGE L. SCHEEL, OF CHICAGO, ILLINOIS.

ELECTRICAL CONNECTION.

1,324,279.

Specification of Letters Patent.

Patented Dec. 9, 1919.

Application filed May 15, 1916. Serial No. 97,704.

To all whom it may concern:

Be it known that I, GEORGE L. SCHEEL, a citizen of the United States, and a resident of the city of Chicago, county of Cook, 5 and State of Illinois, have invented certain new and useful Improvements in Electrical Connections, of which the following is a specification.

My invention relates to improvements in 10 electrical connections especially designed for use in connection with electric lamps.

The object of my invention is the production of a connection of the character mentioned through the medium of which an 15 electric lamp may be so mounted as to prevent surreptitious removal of the same, and whereby at the same time, when desired, the lamp may be disconnected.

A further object is the provision of an 20 electrical connection which will be of simple construction and efficient in use.

Other objects will appear hereinafter.

The invention consists in the combinations and arrangements of parts hereinafter 25 described and claimed.

The invention will be best understood by reference to the accompanying drawing forming a part of this specification, and in which,

30 Figure 1 is a central section through an electrical connection embodying the invention, and

Fig. 2 is a section taken on line $x-x$ of Fig. 1.

35 The preferred form of construction as illustrated in the drawing, comprises a metallic housing or shell 1 in the rearward end of which is mounted a cylindrical block 2 of insulating material. Provided at the 40 rearward side of block 2 are screws or binding posts 3 and 3' for connection with the conductor wires 4 and 4' coöperating therewith. Said conductor wires enter through a conduit 5 which leads from the rearward 45 end of the casing 1. The screws or binding posts 3 and 3' are connected through the medium of bars 6 and 6' of conducting material with annular ball races 7 and 7' respectively which are mounted in the member 2.

50 Arranged in the forward end of housing 1 is a rotatable metallic socket 8 screw-threaded for the reception of the usual screw-threaded plug of a conventional electric lamp. The rearward end 9 of socket 8 is enlarged and formed with an annular

groove 10 for engagement with the balls in the ball race, 7.

Arranged within the portion 9 of socket 8 is a sleeve 11 of insulating material rigidly secured in position by screws 12. Provided at the inner end of sleeve 11 is a channel member 10' of conducting material, the channel or groove in which engages with the balls in the ball race 7'. The member 10' is provided with a stem 13 which engages in the sleeve 11, being securely fastened thereto by longitudinally extending diametric ribs or flanges 13'.

With the construction thus far described, 70 it will be seen that the socket will be freely rotatable in the housing 1 so that in order to permit of a lamp being threaded into said socket, it will be necessary to arrest the movement thereof, and also, after a lamp 75 has been secured in said socket, it will be impossible to unscrew the same, without rotation of said socket being arrested. Also, it will be seen, that although the socket is freely rotatable in the housing 1, a permanent 80 electrical connection is established between said parts, the threaded terminal 8 of the socket being connected through the ball race 7, the balls arranged in the latter and bars 6 with the screw or binding posts 3 and the 85 stem 13 of the member 10', which constitutes the other terminal of the socket, being connected through the ball race 7', the balls arranged in the ball race and bars 6' with the screw or post 3'.

90 In order to arrest movement of the socket, a pin 14 is slidably mounted in a laterally projecting bearing portion 15 on the housing 1. The inner end of the pin 14 is adapted, upon depression of said pin, to enter a 95 circumferential groove 16 formed in the member 11 and engage with either one of the two projections or lugs 17 projecting into the groove 16 as clearly shown in Fig. 2. It is of course apparent that when the 100 pin 14 is depressed into the groove 16, upon attempted rotation of the socket 8, one or the other of the lugs 17 will be brought into contact with said pin 14 and thus the latter will serve to arrest movement of said socket. 105 Said pin 14 is normally held at its outer terminal movement or in inoperative position by means of a helical compression spring 18.

Threaded in the bearing 15 of pin 14 is a 110 screw 19 adapted to engage at its inner end with said pin in order to lock the same

against depression. The screw 19 is employed after a lamp has been threaded into the socket in order to prevent removal of the lamp, it being clear that removal of the lamp 5 will be impossible where depression of said pin is not permitted inasmuch as it is impossible to remove the lamp without arresting rotary movement of the socket. With this arrangement it will be seen that after 10 the screw 19 has been turned to operative position, removal of the lamp may be effected only after said screw has been unscrewed to release the pin 14. If desired a sealing strip 20 of paper or other suitable material 15 may be arranged about the portion 15 covering the screw 19 in order to prevent access thereto. With this arrangement, access to the screw will be possible only upon breaking of the seal 20.

20 While I have illustrated and described the preferred form of construction for carrying my invention into effect, this is capable of variation and modification without departing from the spirit of the invention. I, 25 therefore, do not wish to be limited to the precise details of construction set forth, but desire to avail myself of such variations and modifications as come within the scope of the appended claims.

30 Having described my invention what I claim as new and desire to secure by Letters Patent is:

1. In a device of the class described, the combination of a housing; an electric socket 35 rotatably mounted within said housing and having electrical connection therewith; manually operable means for holding said socket against rotation; means for locking said last mentioned means against depression; and a seal for preventing access to said locking means, substantially as described.
2. In a device of the class described, the combination of a housing; an electric socket 45 rotatably mounted in said housing and having electrical connection therewith; a spring held depressible pin adapted, upon depression, to arrest rotary movement of said socket; and a manually adjustable screw for locking said pin against depression, substantially as described.
3. In a device of the class described, the combination of a housing; an electric socket arranged in said housing; conductor elements on said housing and said socket; a 55 plurality of series of rolling bearing members interposed between said housing and socket whereby the latter is freely rotatable in said housing, said conductors on said members having electrical connection through said bearing members; and means 60 for holding said socket against relative rotary movement in said housing, substantially as described.

4. In a device of the class described, the combination of a housing; an electric socket 65 arranged in said housing; conductor elements on said housing and said socket; a plurality of series of balls interposed between said housing and socket whereby the latter is freely rotatable in said housing, 70 said conductors on said members having electrical connection through said balls; and means for arresting rotary movement in said housing, substantially as described.

5. In a device of the class described, the 75 combination of a housing, an electric socket rotatably mounted within said housing and having electrical connection therewith, said socket having an axial extension within said housing provided with arcuate grooves and 80 lugs separating the ends of said grooves, a radially disposed pin mounted in said housing and adapted upon depression to engage in one of said grooves to lock said socket against rotation and means for normally holding said pin in retracted position, 85 substantially as described.

6. In a device of the class described, the combination of a housing, an electric socket 90 rotatably mounted within said housing and having electrical connection therewith, said socket having an axial extension within said housing provided with arcuate grooves and lugs separating the ends of said grooves, a radial bearing sleeve on said housing, a de- 95 pressible pin slidably mounted therein and adapted when depressed to engage in one of said slots, yieldable means for normally holding said pin retracted and means ex- 100 tending through said sleeve and engaging said pin to prevent the same from being depressed, substantially as described.

7. In a device of the class described, the combination of a housing, an electric socket 105 rotatably mounted within said housing and having electrical connection therewith, said socket having an axial extension within said housing provided with arcuate grooves and lugs separating the ends of said grooves, a 110 radial bearing sleeve on said housing, a de- pressible pin slidably mounted therein and adapted when depressed to engage in one of said slots, yieldable means for normally holding said pin retracted, means extending through said sleeve and engaging said pin to 115 prevent the same from being depressed, and means covering the last mentioned means to prevent access thereto, substantially as de- scribed.

In testimony whereof I have signed my 120 name to this specification in the presence of two subscribing witnesses.

GEORGE L. SCHEEL.
